COPLANAR LOG PERIODIC DIPOLE ARRAY
Alexander Rauch, Red Bank, N.J., assignor to the United States of America as represented by the Secretary of the ArmyFiled June 7, 1963, Ser. No. 286,431
1 Claim. (Cl. 343—792.5)

The invention described herein may be manufactured and used by or for the Government for governmental purposes without the payment of any royalty thereon.

This invention relates to antennas of a type that can be described as logarithmically periodic since their antenna arrays employ logarithmically periodic antenna elements. More particularly, this invention relates to an improvement in a coplanar dipole array disclosed by D. E. Isbell in Institute of Radio Engineers Transaction, Antennas and Propagation, AP-8, No. 3, pp. 260-267, May 1960, called "Log Periodic Dipole Arrays."

The log periodic antenna of Isbell comprises a coplanar array of side-by-side dipole radiating elements with lengths and spacings related by a constant scale factor and repetitive in a logarithmic manner, that is, the physical dimensions and spacings of the dipole elements are uniformly decreased in accordance with a predetermined logarithmic ratio. These elements are mounted on a pair of parallel linear conductors spaced symmetrically about an axis, and fed at one end by a transmission line. Although Isbell's array is compact and simple, its use is limited due to the fact that it presents a substantially constant impedance match only over a narrow band width. For example, in the above mentioned Isbell article, the antenna is only effectively matched over a band width having a ratio of approximately 1.6 to 1. The present invention provides an improved log periodic dipole array which may be operated over a greater band width and still provide a substantially constant impedance.

In accordance with this invention, the two linear conductors which feed and support the dipole radiating elements of the log periodic array diverge symmetrically from the axis of the antenna, while still maintaining the elements on respective conductors in a coplanar relationship. The structure, then, includes two diverging feed conductors such that the spacing between respective distal ends of the conductors and the antenna axis is greater than the spacing between the respective conductors and the axis at the feed ends of the conductors. The consequence of this uniform divergence of the conductors relative to the axis is to provide a substantially constant impedance over a wide frequency range.

The principal object of this invention is the provision of an antenna of the foregoing type which is conveniently matched to the input feed line over a broad range of frequencies.

For a more detailed description of the invention together with other and further objects thereof, reference is had to the single figure of the accompanying drawing, which is a side view of the antenna in accordance with this invention with a two wire feed system illustrated schematically.

Referring now to the drawing, there is shown a log periodic antenna 10 having a pair of open-ended linear conductors 12 and 14 which are symmetrically arranged about the antenna axis 16. Projecting from conductors 12 and 14 over the length of the antenna 10 are a series of logarithmically spaced dipole radiating elements 18, which are aligned in a coplanar array on the conductors. Conductors 12 and 14 are symmetrically positioned with

2

respect to axis 16 to form equal acute angles ϕ with the axis, and the conductors converge toward each other from the left end of the antenna 10, as viewed. An excitation source 22 is coupled directly by means of a two wire transmission line 20 to the converging end of the antenna 10. It will be understood, of course, that antenna 10 may be used for receiving purposes as well as transmitting purposes, the latter being described simply for convenience as illustrative of one application of the antenna. Any suitable means, such as dielectric supports (not shown), may be used to maintain the conductors 12 and 14 in the prescribed angular position relative to axis 16. The angle 2ϕ of convergence of the conductors 12 and 14 is selected such that the impedance of the antenna 10 is matched over a preselected wide range of frequencies to the input transmission line 20.

By way of example, one antenna model that was built and successfully operated over a frequency range of 50 to 1100 megacycles per second employed an angle of 2ϕ equal to 1° , between the feed conductors 12 and 14. This antenna utilized a coaxial cable transmission line and was found to have a substantially constant impedance over a band width ratio of 22 to 1. The antenna impedance of this model varied from 165 ohms at the lower frequency end to 100 ohms at the high frequency end, thereby improving the impedance match of Isbell's log periodic dipole array over a wide range of operating frequencies.

While there has been described what is at present considered to be the preferred embodiments of the invention, it will be obvious to those skilled in the art that various changes and modifications may be made therein without departing from the invention, and it is therefore aimed in the appended claim to cover all such changes and modifications as fall within the true spirit and scope of the invention.

What is claimed is:

40 A wideband constant impedance logarithmically periodic antenna comprising a pair of open ended linear coplanar conductors spaced symmetrically about an axis, each of said conductors having its open end spaced further from said axis than its feed end so as to form an appreciable acute angle having an upper limit of $.5^\circ$ between each said conductor and said axis, a plurality of 45 straight open ended radiating elements logarithmically spaced along said conductors at right angles to the plane of said conductors and having successive ones of said elements extending in alternate directions from opposite sides of said plane, the length of said radiating elements 50 decreasing logarithmically from said open end to said feed end, said conductors and radiating elements being arranged in two-fold symmetry about said axis and transmission line means connected directly across said feed ends of said antenna.
